UNITED STATES PATENT OFFICE.

ISIDOR D. BRAUNE, OF BROOKLYN, NEW YORK, ASSIGNOR OF ONE-THIRD TO BENJAMIN H. KAUFMAN, OF BLOOMFIELD, NEW JERSEY.

SAFETY DEVICE FOR WINDOWS.

1,174,664.

Specification of Letters Patent. Patented Mar. 7, 1916.

Application filed May 26, 1915. Serial No. 30,517.

To all whom it may concern:

Be it known that I, ISIDOR D. BRAUNE, a citizen of the United States, and a resident of Brooklyn, borough of Queens, and State 5 of New York, have invented certain new and useful Improvements in Safety Devices for Windows, of which the following is a specification.

The objects of this invention are to provide improved means for barring a window in order to prevent children or others from falling out of the same when open; to provide such means wherein the bars may be removed from across the window as the window is closed or left across the window as desired; to provide means on the window adapted to raise or lower the bars therewith; to operate said means to throw it into either operative or idle position from an elevated position out of reach of a child; to permit the window to be raised or lowered independent of the bars when desired; to secure simplicity of construction and operation, and to obtain other advantages and results as may be brought out in the following description.

Referring to the accompanying drawings in which like numerals of reference indicate the same parts throughout the several views, Figure 1 is an elevation of a window to which my invention is applied, said window being viewed from the side which is ordinarily exposed at the outside of a house; Fig. 2 is an edge view of the same; Fig. 3 is a view similar to Fig. 1 looking at the inside of the window, the lower sash of which is partially raised together with a bar; Fig. 4 is an underneath view of the lower sash; Fig. 5 is a perspective view showing a certain fork, track and rider, and Fig. 6 is a transverse cross-sectional view taken on line A—A of Fig. 3.

In the specific embodiment of the invention illustrated in said drawings, the reference numeral 1 indicates a window comprising the usual frame 2 and upper and lower sashes 3, 4 respectively, slidably mounted therein. As is usual in windows of this kind the upper sash 3 is shown overlapping upon the outside of the lower sash 4 so that the lower sash may be raised or the upper sash lowered to open the window. The present invention contemplates a means for barring the window opening when the

sash is opened and it will be obvious from 55 the following description that the invention may be applied to either upper or lower sash.

The present disclosure illustrates the invention arranged more particularly to bar 60 the lower portion of the window and to this end a vertical slideway is provided at each side of the window. Obviously such a slide-way may be made in various manners but for illustrative purposes guide strips 5, 5 65 are arranged vertically, one on either side of the window and spaced from the frame by inwardly bent ends 6, 6 which are bent again toward each other to form portions 7, 7 parallel to the body portion of the strips 70 adapted to be bolted or otherwise secured to the frame. As shown in the drawings, the strips 5, 5 are positioned substantially at the side edges of the sashes and extend from the window sill upwardly above the top of 75 the lower sash. A housing 8 between the window frame and each strip 5 is narrow enough to leave a vertical slot 9 between its outer vertical edge and the strip, thus forming the slideway. 80

Positioned transversely across the window are a plurality of bars 10, one above the other, extending at their ends through the slcts 9 and connected therat by flexible members such as the chains 11 whereby as 85 the top one is raised the other bars will follow successively with a space left between dependent upon the extent of chain left between the bars. Obviously the same length of chain should be provided between both 90 ends of the bars so that they will be raised evenly. Upward movement of the bars is limited in any suitable manner, so as to prevent the lowest movable bar from being raised so far as to allow a person's body to 95 pass thereunder. To this end a bar 12 is preferably secured fast with respect to the strips 5 at their lower ends from which the lowest movable bar 10 has limited movement upward. 100

At each side of the lower sash is cut a vertical slot 13 in the portions of the frame forming the slideways for the lower sash of the window, said slot affording an opening through which a lifting member upon the 105 window may project through the frame and draw upon a flexible member 14 connected with the bars for elevating the same as the

window is opened. In carrying out the detailed construction for effecting this result, suitable sleeves 15, 15 are provided at the underside of the lower sash extending longitudinally of the lower reach and adjacent the ends thereof. Within these sleeves are slidably mounted the stem portions 16 of forks 17 said forks having bifurcated ends or prongs 19 extending through the same 5 upon opposite sides of a vertical way or track 19. Slidably mounted upon said track is a rider 20 transversely of the track and transversely of the prongs, so that the prongs may underlie the said rider on opposite sides 10 of the track so as to engage the same evenly and raise it without tilting. To said rider is connected the flexible member 14 which extends below the window sill making substantially a quarter turn around a pulley 21 15 then outward to a pulley 22 turning upward upon the outside of the window frame between the same and the bars 10 to a pulley 23 at the top of the vertical strip 5 over which said flexible member turns downward again and is connected at its lower end to 20 the bars. As shown in the drawings said flexible member 14 is a cord or rope and is connected to the chain 11 by a hook 24. By this arrangement of the pulleys and the flexible member, as the window is raised with 25 the prongs 18 of the fork 17 underlying the rider 20 the bars 12 will be raised also.

Means are preferably provided for retaining the bars in their raised position and 30 allow the window to be lowered without lowering the bars. To this end a spring catch 25 of any suitable construction is positioned so that the latch 26 thereof is in the path of the bars 10 and at a proper height 35 so as to underlie the top one of said bars when at its uppermost position. Preferably the underside of said latch is beveled so that raising the bar presses the latch in as the bar passes after which the latch springs outward again underneath the bar. From the 40 inner end of the latch extending toward the window frame is a connecting member 27 which may be drawn upon to retract the latch and release the bar so that it may be lowered. Connected to the inner end of this 45 member is one arm 28 of a swinging member 29, the other arm 30 of which is inclined and adapted to be engaged and swung by the projecting prongs 18 of the fork 16.

50 In order to retain the bars in their raised position across the window and allow the window to be raised or lowered at will without affecting the bars, the swinging member 29 is in a plane further from the side of the window sash than the plane of the rider 20, so that the fork may be caused to underlie and raise the rider but not extended far enough to engage and swing the member 29.

55 When it is desired to lower the bars the fork may be extended further so as to engage the

member 29 and release the latch 26 so that as the window is lowered the bars will also be lowered.

For operating both forks simultaneously to extend or retract them a lever 31 is 60 pivoted to the side rail of the lower sash preferably upon its outer side and projects upwardly between the sashes above the lower one, said lever providing a handle at its upper end above the lower sash. Said lever 65 is fulcrumed as at 32 intermediate of its ends and at its lower end is connected with the stem portion of the fork at that side of the window. Obviously, therefore, by swinging the lever, the fork 16 connected 70 thereto may be extended or retracted as desired, and in order to extend and retract the other fork simultaneously therewith, the following means are provided.

Extensions 33 upon the inner ends of the 75 fork stems are shown arranged in a horizontal plane adjacent the outer and inner longitudinal edges of the underside of the sash. Said extensions are separated from each other laterally and overlap longitudinally and provide each a plurality of teeth 34 at their facing sides adjacent the ends. A pinion 35 in mesh with the teeth 34 on both extensions is pivoted to the sash between said extensions. In operation, as the 80 one fork is retracted, for instance, the pinion 35 in mesh with the teeth 34 of the extension of said fork is rotated and thereby causes the other fork to be drawn inward an equal amount. Obviously the distance 85 which the forks project beyond the sash is regulated by the amount which the lever is swung, so that in one extreme position of the lever the forks are entirely retracted so the window may be raised or lowered entirely independent of the bars. In the opposite extreme position of the lever the forks are extended as far as they will go and will underlie and raise the rider 20 and bars 10 and when raised sufficiently will also engage 90 the swinging member 29 to retract the latch 26 so as the sash is lowered again the bars will also lower. Between the two extreme positions the lever may be positioned at an intermediate position so that the forks will 95 be partially extended and underlie the rider to raise it and the bars, but not sufficiently extended to engage the swinging member 29. Consequently the sash may be raised its full extent and the upper bar 10 will be engaged 100 and held by the latch 26 allowing the sash to be raised and lowered at will without affecting the bars. When it is desired to release and lower the bars, the lever is swung to its extreme position to extend the forks 105 their full amount and the sash raised to trip the catch and then lowered, taking the bars with it.

Obviously detail modifications and changes may be made in manufacturing my im- 110

proved safety device without departing from the spirit and scope of the invention, and I do not wish to be understood as limiting myself except as required by the following claims when construed in the light of the prior art.

Having thus described the invention, what I claim is:—

1. In a window, the combination with a sash adapted to be raised and lowered, a plurality of slidable bars adapted to be lowered in idle position or raised to extend across and bar the window opening, means for raising the bars as the window sash is raised, and releasable means for retaining said bars in raised position when the sash is again lowered.
2. In a window, the combination with a sash adapted to be raised and lowered, a plurality of slidable bars adapted to be lowered in idle position or raised to extend across and bar the window opening, means for raising the bars as the window sash is raised, releasable means for retaining said bars in raised position when the sash is again lowered, and a member adapted to be operated by raising the window for releasing said retaining means and allow the bars to be lowered.
3. In a window, the combination with a sash adapted to be raised and lowered, a plurality of slidable bars adapted to be lowered in idle position or raised to extend across and bar the window opening, a vertical track adjacent the sash, a rider on said track connected to said bars for raising the same, means on the window sash adapted to raise said rider on the track as the sash is raised, and releasable means for retaining said bars in raised position when the sash is again lowered.
4. In a window, the combination with a sash adapted to be raised and lowered, a

plurality of slidable bars adapted to be lowered in idle position or raised to extend across and bar the window opening, a vertical track adjacent the sash, a rider on said track, flexible means connecting said rider to said bars for raising the same as the rider is raised, means on said sash adapted to underlie said rider to raise the same and the bars, and releasable means for retaining the bars in raised position.

5. In a window, the combination with a sash adapted to be raised and lowered, a plurality of slidable bars adapted to be lowered in idle position or raised to extend across and bar the window opening, a vertical track adjacent the sash, a rider on said track connected to said bars for raising the same, a latch for retaining the bars in raised position, a releasing member for tripping said latch, and a raising member on the sash adapted to be partially extended to engage and raise the rider for raising the bars or entirely extended to engage the releasing member and trip the latch whereby the bars may be lowered.

6. In a window, the combination with upper and lower sashes adapted to be raised and lowered, a plurality of bars slidable in a plane substantially parallel to the planes of the sashes at a distance therefrom whereby said bars may be operated without interfering with said sashes, a rider at the side of the lower sash, releasable means for engaging said rider and raising it by raising said sash, and a flexible member secured to said rider and passing over pulleys at the bottom of said window and others above the middle of said window and connected to said bars whereby raising said rider will raise the bars, and releasable means for retaining said bars in raised position when the sash is again lowered.
